UNITED STATES PATENT OFFICE.

JOHN W. GRAVES, OF COVINGTON, TENNESSEE, ASSIGNOR TO INTERNATIONAL COTTON COMPANY, OF BOSTON, MASSACHUSETTS, A CORPORATION OF SOUTH DAKOTA.

COTTON-GIN ROLLER.

No. 874,910.

Specification of Letters Patent.

Patented Dec. 24, 1907.

Original application filed October 12, 1904, Serial No. 228,195. Divided and this application filed March 3, 1905, Serial No. 248,232.

To all whom it may concern:

Be it known that I, JOHN W. GRAVES, a citizen of the United States, and a resident of Covington, in the county of Tipton, State 5 of Tennessee, have invented certain new and useful Improvements in Cotton-Gin Rollers, of which the following is a full, clear, and exact description.

This application is a division of my application filed October 12, 1904, Serial No. 10 228,195, and relates to certain improvements in cotton-gin rollers hereinafter set forth.

Referring to the drawings forming part of 15 this specification, Figure 1 is a transverse section of a portion of a cotton gin roller showing my improvements applied thereto. Fig. 2 is a face view of a portion of such roller, and Fig. 3 is a detail side view of one 20 of the ginning teeth plates.

The reference numeral 1 designates the main gin cylinder, a small section only of 25 which is illustrated; but which is fully set forth in my said original application Serial No. 228,195. Upon the face of said cylinder are located the alternate sets of ginning teeth and rubbing surfaces constituting my invention. Said teeth are formed integral with plates 2, as shown in Fig. 3; while between said series of teeth 4 are located the rubbing sections 3. Said plates are formed 30 of suitable metal and are comparatively thin; while the rubbing sections are each composed of a considerable number of sheets of leather, as shown in Fig. 2; the latter being held in

position by extending beneath the overhanging shoulders 9 of said plates. To lock said plates in position, they are each formed with two legs 7 straddling a bar 6 set slightly into 40 the surface of the cylinder 1, as shown in Fig. 1. In a groove in one side of said bar and in corresponding spaces formed by the notch 7^a in one of said legs 7, is inserted a rod 8 which, when withdrawn, permits of said plates removal, but when in place firmly locks the latter against displacement. Suitable bolts 45 secure said bars in place.

Between every adjoining pair of plates 2 is placed a blank plate 2^a, constructed in every 50 particular like said plates 2 but without the combing teeth 4; their object being to separate said teeth from each other for a suitable space. These blanks are so located in every two following groups of teeth that the teeth

in one group will come in the same diametrical plane with the blanks in the groups immediately preceding and following. By "diametrical plane" I mean to designate the same plane cutting the axis of the cylinder at right angles. The object of this is to insure that any seed cotton which may have partially escaped the teeth of one group owing to having come more or less between the teeth of two adjoining plates, may be sure to be met by the teeth of the following group. In other words, the seed cotton acted upon at one point by one set of teeth will be acted upon at another point by the next succeeding teeth, and so be more thoroughly denuded of its fiber, through this staggered arrangement of the said blanks.

I have discovered that the friction surfaces formed by the edges of the leather sheets 3 located in planes cutting the cylinder's axis transversely, produce much better 75 results than when the leather sheets extend either parallel with said axis, or more or less obliquely therewith. In the latter, or well known arrangements, the leather is more liable to lay over or be tipped more or less out 80 of position. I also find that a ginning roller having its periphery composed of alternate sections of friction surfaces and combing, carding or abrading surfaces, accomplishes the best possible results; the alternate rubbing and combing actions following each 85 other in quick succession upon the seed cotton serving to more thoroughly denude the latter of its fiber.

What I claim as my invention and for 90 which I desire Letters Patent is as follows, to wit:—

1. A main gin cylinder having bars fixed upon its periphery parallel with its axis, and combing plates bifurcated to fit upon said 95 bars, in combination with rods located in grooves formed in said bars and notches in said plates.

2. A cotton gin roller comprising a cylinder and friction and combing sections arranged alternately on the periphery of said cylinder, said combing sections having shoulders which are constructed to overhang the friction sections and interlock therewith for holding the same against outward movement on the cylinder.

3. The combination with a cylinder, of bars fixed to its surface, bifurcated plates

straddling said bars and having overhanging shoulders, means removably locking said plates to said bars, and leather sheets supported on edge upon said cylinder's surface 5 and held in place by extending beneath said shoulders.

In testimony that I claim the foregoing in-

vention, I have hereunto set my hand this 21st day of January, 1905.

JOHN W. GRAVES.
